(57) **CLAIM**

The ornamental design for a combined car tissue and trash bin, as shown and described.

DESCRIPTION

FIG. 1 is a perspective view of a front view of a combined car tissue and trash bin according to our new design;

FIG. 2 is a front view thereof;

FIG. 3 is a rear view thereof;

FIG. 4 is a top view thereof;

FIG. 5 is a bottom side view thereof;

FIG. 6 is a left side view thereof; and,

FIG. 7 is a right side view thereof.

The broken lines in the figures indicate stitching and form a part of the claimed design.
